G. S. Walker's Extension & Step Ladder.

PATENTED

Fig. 3

FEB 4 1868

741 Fig. 1

United States Patent Office.

GEORGE S. WALKER, OF ERIE, PENNSYLVANIA.

Letters Patent No. 74,177, dated February 4, 1868.

IMPROVED STEP AND EXTENSION-LADDER.

The Schedule referred to in these Letters Patent and making part of the same.

TO ALL WHOM IT MAY CONCERN:

Be it known that I, GEORGE S. WALKER, of Erie, in the county of Erie, and State of Pennsylvania, have invented a new and improved Step and Extension-Ladder combined; and I do hereby declare that the following is a full, clear, and exact description thereof, which will enable others skilled in the art to make and use the same, reference being had to the accompanying drawings, forming part of this specification.

Figure 1 is a front view of my ladder combined.

Figure 2 is a section of the same through the line *x x*, fig. 1.

Figure 3 is a perspective view of the invention when arranged as a step-ladder.

Figures 4 and 5 are detail views of the hooks and arm, and showing their operation.

Similar letters of reference indicate corresponding parts.

This invention relates to a ladder which can be used as an extension-ladder or as a step-ladder, as required. It consists of one ladder working with sliding contact upon another, and extended by a crank, cord, and pulley when used in one way, and rested against the same ladder when used as a step-ladder, by means of devices contributing to this end, and perfecting the whole, as will be hereinafter more fully set forth.

In the drawings, *A* is the extending-ladder, which slides upon lower ladder *B*. Four iron guides, *e*, made as shown, and bolted or otherwise secured to the inner faces of the uprights of the ladder *B*, serve to allow the ladder *A* a sliding motion, and at the same time retain it from separating from the ladder *B*. One of the lower rounds of the ladder *B* revolves, and is furnished with a crank-handle, *d*, for turning it, and thus winding up the cord *b*, which passes over a pulley, *m*, and is thus the means of extending the ladder *A*, for the said cord, after passing through the pulley, descends, and is attached to the bottom round of the ladder *A*. This round also is set loosely in the ladder *A*, so that it is permitted a partial rotation for the working of the hook-device, now to be described.

Hooks *i* and an arm, *n*, are secured rigidly on the last-described round, and in such a position that the hooks will slip past the rounds of the ladder *B* without catching when the ladder *A* is being raised or extended by the cord and crank. The arm *n* prevents the said hooks from catching when the ladder *A* is lowered by the cord and crank, and the only time that the hooks will catch on any one round of the ladder *B* is when the hooks have passed the round, and the arm *n* has not passed the same round, but rests against it. When the hooks and arm are in this position, if the ladder *A* is lowered, the hooks will catch on the said round immediately, thus holding the ladder *A* extended, so that a person can ascend it for any purpose. This peculiar action of the hooks and arm is shown at figs. 2, 4, and 5, which depend for their proper operation upon the tension of the cord, due to the weight of the ladder *A*, which tension holds the round in a certain position, yet allows it to yield, and thereby permit the hooks or arm to pass the rounds of the ladder *B* when the said hooks or arm come in contact therewith in the operation of raising or lowering the ladders *A*. The proper relative position of the hooks and arm on the round is such that they shall enclose a small angle between them, as shown in figs. 2, 4, and 5, and their proper position in reference to the cord is that of, or approximating to, a right angle, with the said cord, so that when the hook passes any round, the arm will follow immediately, and keep the hook in a proper position to catch on the round if the ladder *A* should be lowered before the arm has passed the round, as shown at fig. 5, for, when the hooks have passed, and the arm remains in contact with the round, as shown, if the ladder *A* be then lowered, the hooks will catch on that round, and hold the ladder extended, as shown at fig. 1. Thus the ladder can be extended or lowered at will by means of the crank-handle *d*, and the hook *i* caught on any round desired, by simply lowering the ladder after the hooks have passed, but while the arm still rests against the particular round of the ladder *B*.

When it is desired to convert the extension-ladder into a step-ladder, it is only required to draw the ladder *A* from its guides *e*, and set it against the ladder *B* in the manner shown in fig. 3. The hooks *i* are to be caught under the top round of the ladder *B*, and the cord *b* drawn down and caught in a hook, *h*, set into the round *k*, as shown, whereby the cord serves as a brace to keep the ladders from spreading apart.

My invention is durable, simple, cheap, and efficient, and supplies a want long felt.

I am aware that pivoted catches have been used on extension-ladders for the same purpose as in my case,

as, for instance, in the patent of C. G. Udell, March 26, 1867; therefore I do not wish to claim broadly the use of hooks and arms, but

What I do claim as new, and desire to secure by Letters Patent, is—

1. In a combined extension and step-ladder, the hooks *i* and arm *n*, in combination with ladders *A* *B*, cord *b*, pulley *m*, and crank-shaft *a* *d*, all constructed, arranged, and operating substantially as described and for the purpose specified.

2. In combination with the above, I claim the hook *h* and guides *e*, substantially as described.

3. The combined extension and step-ladder, constructed substantially as described, and consisting of the sections *A* *B*, hooks *i*, arm *n*, guides *e*, pulley *m*, cord *b*, and crank-shaft *a* *d*, all arranged and operating substantially as set forth.

GEORGE. S. WALKER.
